Arthur Evans Jr.
WITNESS

BY *Victor J. Evans*
ATTORNEY

UNITED STATES PATENT OFFICE

ALLEN J. EVANS AND ROBERT T. RAINES, OF ATLANTA, GEORGIA; SAID EVANS
ASSIGNOR TO SAID RAINES

AUTOMATIC POWDER BRUSH

Application filed April 5, 1930. Serial No. 441,956.

Our present invention has reference to a brush designed for automatically applying parting or talcum powder to stereotype dry mats and to smooth or slicken the face of the mat, and the object of the invention is the provision of a brush for this purpose which will deliver a polishing powder through the bristles thereof to more effectively assist in the application of such powder on the mat.

To the attainment of the foregoing the invention consists in the improvement hereinafter described and definitely claimed.

In the drawings:

Figure 1 is a side elevation of the improvement.

Figure 2 is a sectional view approximately on the line 2-2 of Figure 1.

Figure 3 is a transverse sectional view on the line 3-3 of Figure 1.

Figure 4 is a similar view but showing the valve plate moved to uncover the openings between the valve plate and brush head.

The brush is of the usual construction, the same having embedded in the head 1 thereof the usual bristles 2. The brush, however, throughout its length, is provided with spaced apertures or openings 3.

Fixedly secured on the top of the brush head there is a substantially rectangular box or container 5 for a suitable polishing powder. The container 5 has hingedly secured thereto, as at 6, a hollow cover 7. The container is of a box-like formation and has on one of its sides a spring clip 8 that is formed with an opening or is apertured to receive therethrough a keeper element 9 that is fixed to one side of the container.

The bottom of the container is provided with a series of spaced openings 10 which are in register with the openings 3 in the brush head 1.

Slidable on the bottom of the container there is a valve plate 12. The outer edge of the

valve plate is offset to form the same with a handle or grip 13, and the said valve plate is provided with a series of openings 14 which are normally out of register with the openings 3 and 10.

Fixedly secured in the container 5 there are spaced spring plates 15 which normally overlie the valve plate 12, and fixed on the valve plate there are guide lugs 16 which contact with one of the edges of the guides 15. Also fixed on the valve plate there are the offset ends of clips 17 which overlie the guides for more effectively holding the spring plates in frictional contact with the valve plate 12.

Removably but fixedly secured in the container 5 there is one end of a coil spring 18. The valve plate is slotted at spaced intervals at approximately the center thereof and the metal bound by these slits is bent upwardly and from thence rounded to form the same with a hook 19 and the said hook engages with the second end of the spring 18.

The spring 18 normally influences the valve plate to cover the openings 3 but obviously a slight pressure upon the offset or handle 13 of the valve plate will bring the openings or apertures 10 in register with the openings 3. The inward movement of the valve plate is limited by the contact of the handle or finger piece 13 with one of the sides of the brush head and from the foregoing description, when read in connection with the accompanying drawings, the simplicity of the construction and the advantages thereof will, it is thought, be understood so that further detailed description will not be required.

Having described the invention, we claim:

A brush having an apertured head, a container for a cleansing powder fixed on the top of the head having apertures which register with those in the head, an apertured valve plate slidable on the bottom of the container and having a handle end which

is passed through the container, spring guides fixed on the container overlying the valve plate, lugs on the plate contacting with the edges of the guides, and spring means between the plate and container for normally holding the apertures of the plate out of register with the apertures in the bottom of the container and in the brush head, and clips fixed to the valve plate and overlying the guides for forcing the guides into tight frictional contact with the valve plate.

In testimony whereof we affix our signatures.
